UNITED STATES PATENT OFFICE.

HARRY S. SHERANSKY, OF ATLANTIC CITY, NEW JERSEY.

TORPEDO AND MINE DEFENSE FOR VESSELS.

1,299,243.

Specification of Letters Patent.

Patented Apr. 1, 1919.

Application filed September 5, 1917. Serial No. 189,745.

To all whom it may concern:

Be it known that I, HARRY S. SHERANSKY, a citizen of Russia, residing in Atlantic City, county of Atlantic, State of New Jersey, 5 have invented a new and useful Torpedo and Mine Defense for Vessels, of which the following is a specification.

My present invention relates to a novel construction and arrangement of a torpedo 10 and mine defense for vessels, wherein the vessel is protected from injury when passing through a mine field and is also protected from injury from torpedoes.

My invention consists, in its broad and 15 generic scope, of a novel construction and arrangement of floatable nets, certain of which are adjustable with respect to the sides of the vessel, provision being made for raising them when the vessel is not in danger 20 so that the speed of the vessel will not be materially retarded.

It further consists of a novel construction 25 of the character stated, wherein the protecting devices are made in sections so that when the ship approaches its harbor or is free from danger, the defensive apparatus can be disconnected so that it will not interfere with the docking of the vessel.

It further consists of a novel apparatus of 30 the character stated which is made in detachable sections, which are provided with propelling mechanisms which can be operated by a hydro-plane or aeroplane carried by the defensive apparatus, it being 35 understood that independent engines can be employed for this purpose, if desired, so that the defensive apparatus can be disconnected from the vessel and serve as a landing and discharge platform for aeroplanes.

It further consists of novel means for adjusting the relative position of the defensive apparatus with respect to the vessel to be 40 protected.

It further consists of a novel construction 45 of protecting apparatus for vessels which, if desired, may be utilized as a storage place for fuel or other material.

Other novel features of construction and advantage will hereinafter more clearly appear in the detailed description.

For the purpose of illustrating my invention, I have shown in the accompanying drawings a typical embodiment of it which is at present preferred by me, since this embodiment will give in practice satisfactory and reliable results, although it is to be un-

derstood that the various instrumentalities of which my invention consists can be variously arranged and organized and that my invention is not limited to the precise arrangement and organization of these instrumentalities as herein shown and described. 60

Figure 1 represents a top plan view of a torpedo and mine defense for vessels embodying my invention and illustrated in conjunction with a vessel. 65

Fig. 2 represents a side elevation of my device.

Fig. 3 represents a side elevation of the parts seen in Fig. 2, certain of the parts being 70 shown in a different relation from that seen in said figure.

Fig. 4 represents a section on line 4—4 of Fig. 1.

Fig. 5 represents a section on line 5—5 of 75 Fig. 1.

Similar numerals of reference indicate corresponding parts.

Referring to the drawings:—

1 designates the vessel to be protected and 80 such vessel may be of any desired or conventional type. 2 designates the torpedo and mine defense which is made in two sections 3 and 4, which are connected together at the stern of the boat by means of a fastening device 5 and at the front of the boat by means of a fastening device 6. As shown, these fastening devices consist of pins which are adapted to pass through apertures in the ends of the sections. Each section is provided with a desired number of brackets 7, through which are adapted to pass bars 8 carried by the vessel, and a key 9 is employed which passes through the bar 8 and engages the brackets 7 to maintain the defense apparatus in fixed position with respect to the vessel. Each section of such apparatus is constructed in substantially the same manner, except that a right and a left hand section is formed which curve toward 95 each other at their forward ends.

Each section consists of an inner float 10 which forms an auxiliary vessel or float extending longitudinally substantially the length of the boat and preferably formed of 105 a metal framework enveloped by a waterproof coating 11 of any desired nature. I have found in practice that certain grades of wax treated in a special manner give good results but any desired cementitious material 110 may be employed, either alone or in combination with other materials. These floats 10

are secured by means of beams 12 to longitudinally extending angle irons 13 which are preferably sectional and secured together in any desired manner. By forming these longitudinally extending angle irons in section, the device can be readily adapted to coöperate with any desired length of vessel which is to be protected.

14 designates lazy tongs, the levers of which are pivotally connected as at 15 with its respective angle iron 13. The lazy tongs 14 are also pivotally connected with longitudinally extending bars 16 and 17 as at 18 and 19, respectively, these bars forming the supports for the auxiliary double floats or double nets. The bar 16 has connected thereto the vertically extending float support 20 which is provided at its lower end with outwardly extending base flanges 21, see Fig. 4, on which the inturned flanges 22 of the open work metal of the float 23 are supported when such float is in operative position as seen in Fig. 4. The body portion of the float 23 is covered with a waterproof coating 24. Any desired means may be provided for raising the float 23, and in order to show a conventional type, I have illustrated a cable 25 connected with the bottom of the float and passing over rollers 26, said cable being designed to be operated by any desired means, such as for example, an auxiliary engine, not shown but present in vessels now in use. The longitudinally extending bar 17 pivotally connected to the lazy tongs as described has connected thereto the vertical support 27 corresponding in construction to the support 20 and coöperating with an outer auxiliary float 28 constructed and operating in a similar manner to the float 23 and provided with a cable 29 which passes over rollers 30 and is adapted to be operated in any desired manner to effect the raising and lowering of such auxiliary float 28. As an additional protection, the fulcrum means 18 and 19 are secured to brackets 31 to which is connected a lower rail 32, said lower rail being connected by bars 33 with an upper rail 34. The upper rails 34 have passing transversely therethrough the bars 35 which also pass through the angle irons forming the rails 34. An intermediate T-shaped bar 37 is fixed to the bars 35 and the upper rails 34 are loosely mounted on the bars 35. By such construction, the rails 34 and bar 37 form a receiving and discharging platform for hydroplanes, aeroplanes, or their equivalents. In order to provide for the passage of a hydroplane, for example, on to the receiving platform, the ends of the rails 32 have pivotally connected therewith one end of the arms 38, said arms being pivotally connected to one end of arms 39, the other ends of which are pivotally connected with the upper rail 34.

65 40 designates flexible links preferably

bowed and having their ends connected with the bar 37 and with the arms or links 38 and 39. The bars 35 are connected by means of cables 41 with any desired mechanism for winding up and unwinding said cables to effect the expansion or collapse of such framework. Any desired mechanism may be employed to effect the expansion and contraction of the lazy tongs and in order to illustrate one form of construction for accomplishing this purpose, I have illustrated the free ends of the lazy tongs as being connected with cables 42 and 43 which can be operated by any desired or conventional type of engine driven drum, such as is present on vessels now in use, and it is therefore believed to be unnecessary to illustrate or describe such parts. The sections of the protecting apparatus are capable, as described, of being detached from the vessel and any desired means may be employed for moving them through the water, and as illustrated, this can be accomplished by means of the hydroplane mounted on the landing and receiving platform. This section is provided with a propeller 44 mounted on a shaft 45 carried by a housing 46, which is braced by a bar 47 on which it is laterally adjustable. See Figs. 2 and 3. Mounted in the housing 46 is a shaft 48 which is intergeared with the propeller shaft 45. The shaft 48 is provided with a clutch mechanism 49 whereby its gear 50 may be thrown into and out of gear with the gear 51 driven by the hydroplane, it being understood that the hydroplane is clamped in position in any desired manner. By such construction, the sections of the protected apparatus will be detached from the vessel and utilized as landing and receiving stations for the hydroplanes and may also be moved to any desired location by means of a hydroplane.

The floats, such as 10, 23 and 28, may be employed also as storage for fuel or other supplies and are preferably made in sections and in Figs. 2 and 5, I have shown one of the floats as forming a storage tank 52 having a controllable closure 53. In the use of my novel torpedo and mine protector for vessels, the sections are disconnected at one end and the vessel moved thereinto, after which the sections are closed and each section is fixed with respect to the vessel. The intermediate and outer floats are normally in raised position, as seen in Fig. 5, and when the danger zone is entered, the lazy tongs are actuated to position such floats the desired distance from the hull of the boat. The cables 25 and 29 are then actuated to permit the intermediate and auxiliary floats to sink to the position indicated in Fig. 4. As soon as the danger zone has been passed, the intermediate and outer floats are raised and the lazy tongs actuated to bring such floats in close proximity to

the vessel so that the speed of the vessel will not be materially retarded. The intermediate and outer floats may also be adjusted longitudinally of the vessel by the proper 5 actuation of the cables. When the vessel passes beyond the danger zone or enters a harbor, the protecting mechanism may be detached so that there is nothing to interfere with the proper docking of the boat 10 with respect to the wharf.

As the floats are preferably made of open work metal to which is applied a coating of waterproofing of any desired material, each 15 float is the equivalent of a plurality of metal nets, so that if a torpedo should strike the outer float, it would explode before meeting the intermediate or the inner float, thereby preventing injury to the hull of the vessel which is to be protected. The floats are 20 preferably made in section so that in case one is injured, it can be readily and quickly repaired.

The bows of the intermediate floats 23 are 25 preferably curved inwardly, as indicated at 54, see Fig. 1, and the bows of the outer floats 28 are also curved inwardly and overlap so that a torpedo coming toward the bow of the boat or a mine in the path of the vessel would strike the outer float and the 30 vessel would be protected from injury. Any desired mechanism may be employed to guide the floats when they are being self-propelled, and the bow of the float can have any desired or conventional formation, as 35 the floats form auxiliary vessels, the walls of which are the equivalent of nets.

In accordance with my present invention, I provide a protecting mechanism which does not materially retard the speed of the 40 boat and which can be economically and quickly manufactured and which can be readily assembled with respect to the vessel or disconnected therefrom.

It will be understood from the foregoing 45 that my present invention is designed to be employed, not only in times of war but in times of peace; for example, in times of peace, one or more of the floats of a section can be employed to protect the vessel from 50 the likelihood of injury due to collision with other vessels, icebergs, or any other obstacle.

It will further be apparent that since the floats are preferably of sectional construction, they can be readily lengthened or shortened 55 in order to adapt them to be used in conjunction with any desired length of vessel. By the term "vessel" I intend to include any floating structure which is to be protected.

60 It will now be apparent that I have devised a novel and useful torpedo and mine defense for vessels, which embodies the features of advantage enumerated as desirable in the statement of the invention and the 65 above description, and while I have, in the

present instance, shown and described a typical embodiment of it which will give in practice satisfactory and reliable results, it is to be understood that this embodiment is susceptible of modification in various particulars without departing from the spirit or scope of the invention or sacrificing any of its advantages. 70

Having thus described my invention, what I claim as new and desire to secure by Letters Patent, is:—

1. A torpedo and mine defense for vessels, comprising a plurality of floatable members spaced from each other and extending longitudinally of the vessel and attachable thereto, said floats having a receiving and launching platform for aeroplanes, propellers carried by said floatable members and means to operatively connect said propellers with the driving mechanism of said 85 aeroplanes.

2. The combination with a vessel, of an attachable frame supported by it, said frame being provided with laterally extending collapsible supporting members projecting from the sides of the vessel, a plurality of vertically adjustable floats carried by said members, and means supported on said collapsible members to form a vertically adjustable aerial platform. 90

3. The combination with a vessel, of an attachable frame supported by it, said frame being provided with laterally extending collapsible supporting members projecting from the sides of the vessel, a vertically adjustable aerial platform carried by said members, and means supported on said collapsible members below the deck line to form a plurality of vertically adjustable barriers against torpedoes and mines. 95

4. The combination with a vessel, of a sectional attachable frame supported from the vessel, each of said frame sections being provided with laterally extending collapsible supporting members projecting from the sides of the vessel, means for expanding and collapsing said members, a plurality of floats extending longitudinally with respect to the vessel and carried by said members, means for vertically suspending said floats below 110 the water line of said vessel, and means for raising said floats out of the water, aerial platforms carried by said floats, and means for elevating and collapsing said platform. 115

5. The combination with a vessel, of a 120 sectional attachable frame supported from it and encompassing said vessel, each of said sections being provided with collapsible supporting members adapted to be projected laterally from the side of the vessel, a plurality of longitudinally extending auxiliary vessels suspended from said members, a longitudinally extending aerial platform supported on said members, means for lowering and raising said auxiliary vessels with re- 125 130

spect to said members, means for elevating and collapsing said aerial platform with respect to said outriggers, and means for independently operating said members.

- 5 6. The combination with a vessel, of a sectional frame supported from it, each of said sections being provided with collapsible supporting members adapted to be projected laterally from the sides of the vessel, each 10 section having a propeller, a plurality of longitudinally extending floats suspended from said members, a longitudinally extending aerial platform supported on said floats, means for lowering and raising said floats 15 with respect to said members, means for elevating and collapsing said aerial platform, and means for forming a driving connection between an aeroplane supported on said aerial platform and a propeller carried by 20 said frame section for the independent propulsion of each of said frame sections.

7. The combination with a vessel, of a sectional frame supported from it, each of said sections being provided with collapsible 25 members adapted to be projected laterally with respect to the sides of the vessel, a plurality of longitudinally extending floats suspended from said members and curved inwardly at their forward ends, the outer 30 floats overlapping each other at the bow of the vessel, said curved portions being adapted to be brought into longitudinal alinement with each float section, a longitudinally extending aerial platform supported on said 35 member, means for lowering and raising

said floats with respect to said members, means for elevating and collapsing said aerial platform, and means to actuate said members.

8. A sectional frame adapted to be supported from a vessel, each section being provided with laterally expandable and collapsible members, means to actuate said members, a plurality of floats extending longitudinally of the vessel, means for vertically suspending said floats below the water line of said vessel, means for raising said floats out of the water, aerial platforms carried by said floats and provided at their rear ends with depending guide rails adapted to form an auxiliary landing platform for hydroplanes from the surface of the water when the aerial platform is collapsed, and means for elevating and collapsing said platform. 45

9. A sectional frame adapted to be supported from a vessel, each section being provided with laterally expandable and collapsible members, means for expanding and collapsing said members, a plurality of floats extending longitudinally of the vessel and supported by said members, means for raising and lowering said floats, aerial platforms on said floats and consisting of lattice work adapted to form protective means for the superstructure of the vessel, and means for elevating and collapsing said platforms. 50 55
